(57) **CLAIM**

The ornamental design for a set of replacement connectors for an engine control module (ECM), as shown and described.

DESCRIPTION

FIG. 1 is a perspective view of a set of replacement connectors showing my new design affixed to an ECM; FIG. 2 is a top plan view of the design of FIG. 1;

FIG. 3 is a bottom plan view of the design of FIG. 1;

FIG. 4 is a rear side view of the design of FIG. 1,

FIG. 5 is a front side view of FIG. 1;

FIG. 6 is a right side view of the design of FIG. 1;

FIG. 7 is a left side view of the design of FIG. 1;

FIG. 8 is a perspective view of the set of replacement connectors of the design of FIG. 1 shown apart from the ECM;

FIG. 9 is a front side view of the set of replacement connectors of the design of FIG. 8, the rear elevational view being a mirror image thereof;

FIG. 10 is a right side view of the design of FIG. 8, the left side elevational view being a mirror image thereof;

FIG. 11 is a top plan view of the design of FIG. 8; and,

FIG. 12 is a bottom plan view of the design of FIG. 8.

The broken lines showing the ECM in FIGS. 1-7 are illustrative of environmental structure only and form no part of the claimed design.
